UNITED STATES PATENT OFFICE.

TIMOTHY L. TRACY, OF RICHMOND, INDIANA.

DISPLAY COUNTER.

Application filed March 27, 1922. Serial No. 546,966.

To all whom it may concern:

Be it known that I, TIMOTHY L. TRACY, a citizen of the United States, residing in the city of Richmond, in the county of Wayne, State of Indiana, have invented a new and useful Display Counter, of which the following is a full, clear, and comprehensive specification and exposition, the same being such as will enable others to make and use the same with exactitude.

This invention relates to store-furniture, particularly to counters or show cases, and especially to showing and dispensing coffee, and it may be denominated a coffee counter.

The object of the present invention, broadly stated, is the provision of a display counter which is strong and durable in construction, simple in character, neat and attractive in appearance, efficient in practice, and which can be manufactured and sold at a comparatively low price.

More specifically stated, my object is to provide a combined counter and display cabinet, the construction being especially adapted for displaying various grades of coffee at one time, and from which the coffee may be dispensed without materially disturbing the efficient display thereof. The counter being so constructed as to hold therein a maximum amount of bulk coffee, or other open goods, all contained in a minimum space. And also being adapted to give the greatest and most attractive display features.

Other minor objects and particular advantages of the invention will suggest themselves in the course of the following description, and as set forth in the appended claims.

The preferred means for carrying out the principles of my invention in a practical manner is shown in the accompanying two-sheets of drawings, in which—Figure 1 is a front elevation of the entire construction as assembled. Figure 2 is a top plan view thereof. Figure 3 is an end elevation of the same. Figure 4 is a rear side elevation. Figure 5 is a horizontal section as taken, for instance, on the line 5—5 of Fig. 4. Figure 6 is a cross section, as taken on the line 6—6 of Fig. 4. Figure 7 is a detail section, showing the manner of assembly, but taken

for instance on the line 7—7 of Fig. 1, and Figure 8 shows one of the supports for the inclines.

55

Similar indices denote like parts throughout the several views.

In order that the construction, the operation, and the advantages of my invention may be more fully understood and appreciated I will now take up a detailed description thereof in which I will set forth the same as fully and as clearly as I may.

Referring now to the drawings in detail: The central section of the construction includes the main end members 1 and 2 which form solid wooden partitions extending from the floor-line A upward to the top of the central section. Said end members are spaced apart and are parallel with each other, their distance apart being approximately the length of the central section, as shown.

Numerals 3 and 4 denote the rails and numerals 5, 6 and 7 denotes the stiles, together forming the main front frame, in which is located the glass 9 and 10.

Extending from the rail 4 downward to the floor A, and also connecting the members 1 and 2, is the base-board 11.

Connecting the members 1 and 2 in the rear is the back-board 12 at the top, the center rail 13, and the bottom rail 14.

Extending back from near the upper edge of the base 11 is the bottom 15, with its rear edge secured to the rail 13.

85

Connecting the opposing edges of the members 12 and 13, spaced apart and extending vertically, are the stiles 16.

A plurality of glass partitions 17 is located vertically and parallel with each other. They extend from the bottom 15 upward even with the upper ends of the members 1 and 2, one of each extending from a stile 16, at the rear, forward to the glass 9 and 10, thereby dividing the interior of the upper portion of the central section into (6) compartments, substantially as shown.

Fitting between each two of the partitions 17, and between each outermost partition 17 and the members 1 and 2, is an inclined bottom 18. The upper rear end of each of the inclines 18 is secured, as by a bracket clip 19, to the inner face of the back-board 12, as shown in Fig. 6.

The forward lower end of each of the inclines 18 is spaced from the glass 9 and 10, and each is supported by one or more metal rod-like supports 20. Said supports 20 being secured to the underside of their respective inclines, with the lower ends of said supports secured to the bottom 15, as shown in Fig. 6.

Numerals 21 and 22 denote frames, having 10 the respective glass 23 and 24 therein, thereby forming horizontal doors, the two together being of such size as to cover the top of the central section. Said horizontal doors are hinged at the rear to the back-board 12 15 each by a pair of hinges 25.

As is clearly shown in Figs. 5 and 6 the members 1 and 2 project rearward beyond the central section, in order to provide the means for making the end sections of the 20 desired size and shape.

The left-hand end section comprises a substantially square and horizontal top 26, which is supported by a front frame 28, a rear frame 30, and a frame 32.

25 Likewise the right-hand end section comprises a substantially square and horizontal top 27, which is supported by a front frame 29, a rear frame 31, and an end frame 33.

The tops 26 and 27 are located on a lower 30 level than is the top of the central section, and said frames of the end sections extend from their respective tops 26 and 27 to the floor line A, and each set of frames has its members secured together and to their respective members 1 and 2, each forming a hollow square, and the tops 26 and 27 are rigidly secured thereto.

Each of the frames 28, 29, 32 and 33 carries therein a three-ply panel, 34, 35, 36 and 40 37, respectively. The frames 30 and 31 have no panels therein but are open to provide ingress and egress.

From the above it is apparent that we now have a construction to be employed as a 45 counter, or more specifically as a coffee case. The front shown in Fig. 1 being the side next the customer, with the clerk or dealer operating on the other side, in the rear.

The doors covering the central section 50 may be turned back, after which the coffee may be placed in the several compartments filling the compartments each with a distinct grade or kind of coffee. As each section is filled the coffee flows down over the 55 lower end of the incline and runs back a short distance on the bottom 15, but finally when the compartment is full it is apparent that it will appear from the front as though the interior of the case were entirely filled, 60 as the incline would not be seen.

This arrangement also permits the customer to see a large extent of coffee in the front and through the top, but the top will prevent dust or dirt from settling in the coffee, and also will prevent the coffee from 65

being handled by the customer, but at the same time there is easy access for the dealer in the rear to scoop the coffee from the bottom 15, by operating through the spaces between the stiles 16, as there will be no doors or lids to operate the arrangement will facilitate the work.

A coffee mill may be located on one of the tops 26, or 27, and weighing scales may be placed on the other one of said tops, thereby 75 making the dispensing of coffee very handy.

The space below the bottom 15, and the spaces in the end sections below the tops 26 and 27, provide spaces for the storage of surplus stock or other goods, all of said 80 spaces being open to the rear, and like the opening between the stiles 16, they are without closures or doors.

In the upper portions of the members 1 and 2, that is above the tops 26 and 27, there 85 are located panels of glass, as the glass panel 34 shown in Fig. 3.

I desire that it be understood that various changes may be made in the several details of construction from that herein shown and 90 described without departing from the spirit of the invention and without sacrificing any of the advantages thereof which are new and useful and which involves invention.

Having now fully shown, and described 95 my invention, what I claim and desire to secure by Letters Patent of the United States, is—

1. A display counter having a central section, and sections of less height and of 100 greater width than the central section, doors covering the top of the central section, transparencies for the doors, the front of the central section being formed transparent, a bottom on the inside of the central section, said bottom being located near the center vertically of the central section, transparent partitions dividing the interior of the central section above said bottom into a plurality of compartments, an incline located between each two of said partitions and above said bottom, said partitions being secured at their rear upper ends to the back of the central section and projecting from there forward and downward, with their forward 115 lower ends spaced from the front of the central section, and means for securing said incline in said position.

2. A display counter comprising in combination, a central section, end sections of 120 less height and of greater width than the central section and rigidly connected therewith, glass doors covering the top of the central section, transparencies in the front of the central section, a solid bottom throughout the interior of the central section and located near the center vertically thereof, a plurality of transparent partitions extending 125 from said bottom to said doors and from the front to the back of the central section 130

and dividing the interior of the upper portion of the central section into a plurality of compartments, an inclined support located between each two of the partitions and between the two outer partitions and the ends of the central section, means for securing said inclines at their rear upper ends to the

back of the central section, means for supporting the lower forward ends of the inclines in positions above said bottom and 10 rearward of the front of the central section, and means for obtaining access from the rear into each of said compartments.

TIMOTHY L. TRACY.
